(57) CLAIM

The ornamental design for an accessory for use in hair treatment as shown and described.

DESCRIPTION

FIG. 1 is a perspective view of an accessory for use in hair treatment showing our new design;

FIG. 2 is a right-side elevational view thereof;

FIG. 3 is a left-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The claimed design is used to protect hair when using a heated styling device

The broken lines are shown to illustrate symbolic break in length for the accessory for use in hair treatment. The appearance of any portion of the article between the break lines form no part of the claimed design.
